(57) **CLAIM**

The ornamental design for a spray nozzle as shown and described.

DESCRIPTION

FIG. 1 is a perspective view of a spray nozzle embodying the design of the present invention.

FIG. 2 is a front elevational view of the spray nozzle, the rear elevational view being a mirror image;

FIG. 3 is a right side elevational view of the spray nozzle;

FIG. 4 is a top plan view of the spray nozzle; and,

FIG. 5 is a bottom plan view of the spray nozzle.

The broken lines in the drawings depict portions of the spray nozzle that form no part of the claimed design.
